UNITED STATES PATENT OFFICE.

LAURENCE SARTORE, OF PITTSBURGH, PENNSYLVANIA, ASSIGNOR OF ONE-HALF TO
DECIMO FOGLIA, OF PITTSBURGH, PENNSYLVANIA.

STITCHING MECHANISM.

Application filed February 19, 1921. Serial No. 446,502.

To all whom it may concern:

Be it known that I, LAURENCE SARTORE, a citizen of the United States, and resident of Pittsburgh, in the county of Allegheny 5 and State of Pennsylvania, have invented a new and useful Improvement in a Stitching Mechanism, of which the following is a specification.

This invention relates to a stitching mechanism.

One object of the invention is to provide stitching mechanism adapted to the stitching of sausage skins and similar materials which lack the cohesive qualities of fabric, 15 leather, or the like, and which therefore, cannot be readily fed to a sewing machine arranged for ordinary operation.

More specifically the object of the invention is to so arrange and actuate a work 20 supporting carriage relatively to a stitching element, by means of a step by step movement and in synchronism with the operation of the stitching needles, that the material is stitched without being stretched or torn.

25 A further object of the invention is to render the forward step by step movement of the work supporting carriage positive, and to provide means whereby the carriage may be released and automatically returned 30 to starting position after a single complete passage through the stitching element.

35 A further object of the invention is to provide means whereby a sausage skin, or similar material, may be prevented from sagging while passing through the stitching element, thus insuring an even seam throughout the length of the material stitched.

40 A still further object of the invention is to provide mechanism having the above noted advantages which is easily operated and controlled.

45 In the accompanying drawings Fig. 1 is a plan view of the mechanism; Fig. 2 is a side elevation of the same; Fig. 3 is a fragmentary plan view on an enlarged scale with the stitching element proper removed; Fig. 4 is a fragmentary elevation illustrating elements of the mechanism for actuating 50 and controlling the work supporting carriage; Fig. 5 is a detail, partly in elevation, of brake mechanism for limiting forward movement of the work supporting carriage under each single impulse im-

parted thereto; Fig. 6 is a front elevation 55 of this brake mechanism; Fig. 7 is a sectional view through the carriage operating pawl and the means for holding it in and withholding it from engagement with the work supporting carriage; Fig. 8 is a front 60 elevation of the pawl and its associated mechanism; Fig. 9 is a sectional detail view of a stop for preventing backward movement of the carriage, together with the means for holding it in and withholding it 65 from engagement with the carriage; Fig. 10 is a front elevation of this stop mechanism; Fig. 11 is a front elevation of an operating lever for the elements of Figs. 5 to 10 inclusive, showing means for locking the lever 70 in release position; Fig. 12 is a side elevation of the means shown in Fig. 11; Fig. 13 is a fragmentary rear elevation illustrating a portion of the stitching element of the device; Fig. 14 is a fragmentary front elevation 75 of the stitching element of the mechanism, illustrating particularly a tongue for tightening the material undergoing stitching and the means for bringing this tightening tongue into operation; and Fig. 15 is 80 a front elevation of the means illustrated in Fig. 14.

The mechanism, as illustrated, is mounted upon a stand or table 1, which may be of any desired shape or construction. Primarily, the mechanism comprises stitching mechanism proper, which may be a sewing machine of usual design; a carriage for progressively presenting the material to be stitched to the sewing machine; and actuating 85 and controlling means for the sewing machine and carriage.

The sewing machine 2 of the mechanism is shown as power operated by means of an electric motor 3, which is connected by a 95 belt 4 with a fast and loose pulley 5 on a shaft 6. Shaft 6 also carries a double pulley 7 connected by means of belts 8 with pulley 9 on the operating shaft of the sewing machine. The pulley 5 is provided with a clutch 10, which is connected by means of levers 11 and 12 and rocker arm 13 with the operating treadle 14. The motor 3 may thus be permitted to run idly or may be thrown into clutch to actuate the operating shaft of 100 the sewing machine 2.

The carriage operating shaft, or rock shaft, 15 lies beneath the sewing machine

proper, and extends transversely of the sewing machine 2 and the work supporting carriage 16. On shaft 15 is mounted a pawl 17, which engages the teeth of a rack 18 on the under side of carriage 16. This pawl 17 is not directly mounted on the rock shaft, but is pivotally mounted in a bracket 17^a which is rigidly secured to the shaft.

The shaft 15 is oscillated or rocked by means of an eccentric connection with the operating means of the sewing machine 2 (shown in Fig. 13 of the drawings). This connection comprises an arm 19 connected with rock shaft 15, and an arm 20 jointed to the arm 19, the arm 20 being provided with a pin 21 which passes through a slot 22 in balance wheel 23 of the sewing machine. The shaft 15 is thus oscillated at a rate of speed corresponding to that at which the sewing machine 2 is operated. It will be noted that the length of arm 20 is adjustable for adjusting the rate of actuation of rock shaft 15 relatively to the speed of operation of the sewing machine and the length of the stitches taken.

The carriage 16 is provided adjacent either extremity with a bracket 24 having an arm 25 extending over the carriage. Each of the arms 25 carries a pair of spring clips 26 to receive and retain rods 27 for holding the material to be stitched.

If the mechanism is utilized for the stitching of sausage skins, these skins are preferably prepared for stitching by means similar to those described and claimed in my co-pending application Serial No. 446,503, filed February 19, 1921. As prepared by such means, either two or four layers of gut, depending upon the strength of the original gut utilized, are superimposed one on the other; and all are then slit longitudinally to form a strip double the width, and if four layers of gut are used, double the thickness of the original gut. This strip is then to be stitched by the present device to form a sausage bag of increased diameter or of increased strength and diameter. As prepared by the device above noted, the strip of gut is held at each edge between two sections of a rod 27, in position to be stitched longitudinally on lines within and adjacent the rods.

The actual stitching is performed by a pair of needles 28 arranged to be simultaneously operated, and spaced apart the distance desired for stitching the skins along parallel lines adjacent their edges. The needles 28 are preferably supplied with thread from elevated bobbins 29 supported by bracket 30.

As the material being stitched is of such nature that its tendency is to sag when held adjacent its edges by the rods 27, it is highly desirable to provide means for maintaining it taut while being operated upon by the

stitching needles 28. For this purpose a tightening tongue 31 is mounted in the base 32 of the sewing machine in such manner that the material being stitched passes over it as the material is fed to the sewing machine. This tongue 31 may be raised the desired distance above the upper surface of the base 32 by means of a chain 33 and operating means therefor hereinafter described.

In order that the pawl 17 may engage the teeth of rack 18 to cause progression of the work supporting carriage 16, means are provided for causing the pawl to firmly engage behind a tooth of the rack. Such means comprise a tension spring 35 mounted on the under side of the table 1 and connected with the shank 36 of pawl 17 by means of a rod or relatively stiff wire 38. Because of this resilient engagement the pawl 17 may be dragged back over the angular faces of succeeding teeth upon each oscillation of the rock shaft 15, and may engage behind one of the teeth to propel the carriage another step forward.

In order to prevent backward movement of the carriage 16 as the pawl is moved backwardly, the stop 39 is provided. This stop is mounted in a stand 40 and is pressed upwardly by means of the spring 41 therein. The rearward face of stop 39 is beveled to permit the angular face of the rack teeth to depress it and pass by it readily, while the forward face of the stop is arranged to engage behind the teeth to provide a positive check to backward movement of the carriage.

It is desirable that each forward impulsion should cause the carriage to move forward a definite distance, and that the forward movement should be checked immediately upon completion of each oscillation of the rock shaft 15. For this purpose a brake 42 is mounted to bear against the edge of the carriage 16, the brake being held in contact with the edge of the carriage by means of a tension spring 43 connected with the brake by a rod or wire 44. In order to avoid any possibility of carriage 16 being jammed on, or pulled from, its tracks by the force of spring 43, a roller bearing 44^a is mounted in a stand 44 to bear against the side of the carriage and maintain it in position without offering resistance to movement of the carriage in either direction.

It will be noticed that rack 18 does not extend the entire length of carriage 16 but is discontinued an appreciable distance short of each end thereof. There is therefore, no danger that the needles 28 of the stitching element 2 may be broken by the carriage being propelled forward sufficiently far as to cause the rear bracket 24 to strike the needles.

In order that the carriage 16 may be re-

turned to a starting position after the completion of a stitching operation, a counterweight 45 is connected to the rearward extremity of the carriage by means of a cord 46. In order that the counterweight 45 may cause the backward movement of the carriage 16, it is necessary that brake 42 be released, and that stop 39 and pawl 17 be withdrawn from contact with the teeth of rack 18. This release and withdrawal is effected by means of an operating lever 47. The operating lever 47 is pivoted at 48 to the table 1. To this lever are connected means for throwing the brake 42, stop 39, and pawl 17 out of engagement with the work supporting carriage 16. For this purpose brake 42 is provided with a resilient mounting 49 and with a connection 50 from this mounting to the operating lever 47. As previously stated, the brake 42 is normally in engagement with the side of carriage 16. Upon outward movement of lever 47, however, the brake 42 is withdrawn from contact with the carriage against the resistance of spring 43.

The means for withdrawing pawl 17 from engagement with rack 18 comprise a rod 51, connected with the operating lever 47 and passing through slots in uprights 52 and 53 adjacent the shank 36 of the pawl. The inner extremity of rod 51 is provided with a beveled or cam portion 54 arranged to cooperate with shank 36 of the pawl to lift the same against the resistance of spring 35 when operating lever 47 is moved outwardly.

Stop 39, as stated above, is mounted in a tubular stand, or housing, 40, and joined with a plunger 55 which is pressed upwardly by spring 41 therein, so that it engages with the teeth of rack 18. Connected with operating lever 47 is an operating rod 56 supported by a standard or upright 57 and passing through a slot 58 in plunger 55. A light spring 55^a serves to maintain rod 56 in contact with the upper extremity of the slot 58. The extremity of rod 56 is provided with an enlarged head 59 having a beveled face 60 for engagement in the slot 58. Outward movement of operating lever 47 thus serves to depress plunger 55 and withdraw stop 39 from engagement with the teeth of rack 18.

The tension of spring 43 connected with brake 42 tends to maintain the operating lever 47 normally in inward position, with the brake 42, pawl 17, and stop 39, all in engagement with work supporting carriage 16. Means are therefore provided for holding the operating lever in its outer position when so desired. For this purpose an upright 61 is secured on table 1, and lever 47 is passed through a slot 62 therein. A hook 63 operated by a handle 64 thereon may be operated to cause it to engage the lever 47

and secure the same in its outer position, as shown in Figure 11 of the drawings.

In operation of the mechanism, after the work supporting carriage 16 has made a complete traverse of the stitching element 2, treadle 14 is released to disconnect motor 3 from pulley 5, thus causing a cessation in the actuation of the stitching element 2 and rock shaft 15. Operating lever 47 is then pulled outwardly to disengage the means for moving and controlling the carriage 16. As the lever is moved outwardly, brake 42 is first released, pawl 17 is then disengaged from rack 18, and stop 39, which positively prevents backward movement of the carriage, is last withdrawn from engagement with the rack teeth. Counterweight 45 then operates to return carriage 16 to its starting position.

As previously stated, it is desirable to support the gut being stitched and to maintain the same taut while it is being carried through the stitching element of the mechanism, thus preventing wrinkling or pulling of the gut. It is also necessary that the means for this purpose be such that they will not tend to stretch or tear the gut. The purpose is effected by means of a tongue 31, inclined in the direction of movement of the carriage 16, and having connected thereto an operating chain 33. As shown in Figures 14 and 15 of the drawings, this operating chain 33 passes over a pulley 64 mounted on the sewing table 32 and connected at its outer extremity with a lever arm 65 connecting with a bell crank lever 66. One extremity of lever 66 is connected with a coiled spring 67, and the other with a rod 68, which latter connects with operating treadle 14. Spring 67 thus tends to normally maintain tongue 31 in lowered or inoperative position, while operation of treadle 14, in connecting the motor 3, causes a shortening of lever arm 65 and raising of the tongue into operative position.

It will be seen from the above that the gut is under no strain while being fed to the stitching needles, the gut being supported and fed by the movable work supporting carriage; also that the progression of the carriage is automatically regulated during the stitching operation. Owing to the feeding of the gut, it is not necessary that it be dried before it is stitched. This is because the synchronized, step by step, movement of the work supporting carriage prevents pulling of the material, and overcomes the difficulty due to the quality of the material which would prevent withdrawal of the needles in stitching moist gut with a sewing machine of usual design.

It will be further observed that the mechanism is easy to operate; since the operation of the treadle and operating lever serve to cause movement of the work supporting car-

riage during an entire traverse of the stitching element, and also serve to return it to starting position.

The same operation of the treadle which causes propulsion of the carriage also serves to bring into play the means for preventing wrinkling and sagging of the gut during the stitching operation.

As the device illustrated and described above is susceptible of a number of modifications without departing from the spirit of the present invention, the scope of the invention is to be restricted only by the limitations contained in the claims appended hereto.

15. What I claim is:

1. Mechanism for stitching sausage skins and the like while in a moist condition which consists in a stitching element proper comprising a pair of spaced needles, a carriage movable in a line beneath said needles, and means on said carriage arranged to engage and support a section of sausage skin solely along the longitudinal edges thereof in such position as to subject the same adjacent the longitudinal edges thereof to the stitching action of the needles.

2. Mechanism for stitching sausage skins and the like while in a moist condition which consists in a stitching element proper comprising a needle, a carriage movable in a line beneath said needle, means on said carriage arranged to engage and support a section of sausage skin solely along its longitudinal edges in such position as to subject the same along a longitudinal edge thereof to the stitching action of said needle, and means for imparting a forward step by step movement to said carriage.

3. Mechanism for stitching sausage skins and the like while in a moist condition which consists in a stitching element proper comprising a pair of spaced needles, a carriage movable in a line beneath said needles, means on said carriage arranged to engage and support a section of sausage skin solely along the longitudinal edges thereof in such position as to subject the same adjacent the longitudinal edges thereof to the stitching action of said needles, and means for imparting a forward step by step movement to said carriage.

4. Mechanism for stitching sausage skins and the like while in a moist condition which consists in a stitching element proper comprising a pair of spaced needles, a carriage movable in a line beneath said needles, means on said carriage arranged to support a section of sausage skin along the longitudinal edges thereof in such position as to subject the same adjacent the longitudinal edges thereof to the stitching action of said needles, means for imparting a forward step by step movement to said carriage, and independent means for returning said carriage to starting position.

5. Mechanism for stitching sausage skins and the like while in a moist condition which consists in a stitching element proper comprising a pair of spaced needles, a carriage movable in a line beneath said needles, means on said carriage arranged to support a section of sausage skin along the edges thereof in such position as to subject the same adjacent the longitudinal edges thereof to the stitching action of the needles, and a movable member adjacent said stitching element and arranged to project into the path of movement of the carriage to contact the under surface of the section of sausage skin and support the central portion thereof during stitching.

6. Mechanism for stitching sausage skins and the like while in a moist condition which consists in a stitching element proper comprising a needle, a carriage movable in a line beneath said needle, means on said carriage arranged to subject a section of sausage skin along a longitudinal edge thereof to the stitching action of said needle, means for imparting a forward step by step movement to said carriage, and a movable member adjacent said stitching element and arranged to project into the path of movement of the carriage to contact the under surface of the section of sausage skin and support the central portion thereof during stitching.

7. Mechanism for stitching sausage skins and the like while in a moist condition which consists in a stitching element proper comprising a pair of spaced needles, a carriage movable in a line beneath said needles, means on said carriage arranged to support a section of sausage skin along the longitudinal edges thereof in such position as to subject the same adjacent the longitudinal edges thereof to the stitching action of the needles, means and connections for actuating said stitching element and work supporting carriage and a movable member arranged to be projected into the path of movement of the carriage simultaneously with the actuation of the stitching element and carriage to contact the under surface of the section of sausage skin and support the central portion thereof during stitching.

8. Mechanism for stitching sausage skins and the like while in a moist condition which consists in a stitching element proper comprising a needle, a carriage movable in a line beneath said needle, means on said carriage arranged to support a section of sausage skin in such position as to subject the same along a longitudinal edge thereof to the stitching action of said needle, means and connections for actuating said stitching element and imparting a forward step by step movement to said work supporting carriage, and a movable member arranged to be projected into the path of movement of the carriage simultaneously with the actuation of the stitching

- element and carriage to contact the under surface of the section of sausage skin and support the central portion thereof during stitching.
- 5 9. Mechanism for stitching sausage skins and the like which consists in a stitching element proper comprising a pair of spaced needles, a carriage movable in a line beneath said needles, means on said carriage arranged to support a section of sausage skin along the longitudinal edges thereof in such position as to subject the same adjacent the longitudinal edges thereof to the stitching action of the needles, means for imparting a forward step by step movement to said carriage, a brake in yielding engagement with said carriage for limiting forward movement thereof upon each impulse imparted thereto, a stop normally preventing rearward movement of the carriage, and independent means for returning the carriage to starting position.
- 10 10. Mechanism for stitching sausage skins and the like while in a moist condition which consists in a stitching element proper comprising a pair of spaced needles, a carriage movable in a line beneath said needles, means on said carriage arranged to engage and support a section of sausage skin solely along the longitudinal edges thereof in such position as to subject the same adjacent the longitudinal edges thereof to the stitching action of said needles, means for imparting a forward step by step movement to said carriage, and a brake in yielding engagement with said carriage for limiting forward movement thereof upon each impulse imparted thereto.
- 15 11. Mechanism for stitching sausage skins and the like while in a moist condition which consists in a stitching element proper comprising a pair of spaced needles, a carriage movable in a line beneath said needles, means on said carriage arranged to engage and support a section of sausage skin solely along the longitudinal edges thereof in such position as to subject the same adjacent the longitudinal edges thereof to the stitching action of said needles, means for imparting a forward step by step movement to said carriage, and a brake in yielding engagement with said carriage for limiting forward movement thereof upon each impulse imparted thereto.
- 20 12. Mechanism for stitching sausage skins and the like while in a moist condition which consists in a stitching element proper comprising a pair of spaced needles, a carriage movable in a line beneath said needles, means on said carriage arranged to engage and support a section of sausage skin solely along the longitudinal edges thereof in such position as to subject the same adjacent the longitudinal edges thereof to the stitching action of said needles, means for imparting a forward step by step movement to said carriage, and a brake in yielding engagement with said carriage for limiting forward movement thereof upon each impulse imparted thereto.

In witness whereof, I hereunto set my hand.

LAURENCE SARTORE.
